GUN SIGHT

Russell R. Vought, Beverly Hills, Calif.

Application January 17, 1941, Serial No. 374,853

3 Claims. (Cl. 33—46.5)

This invention pertains to an improved gun sight particularly adapted for use on military aircraft such as dive bombers. Generally stated, the invention comprises a combined gun sight and dive indicator whereby the pilot or operator may not only properly direct his plane at the target but in addition execute the dive bombing attack at a predetermined and desired diving angle so that his plane is under predetermined and optimum conditions for the successful completion of the dive bombing attack and proper pull-out without imposing unnecessary strain upon the pilot or his plane.

In dive bombing the plane carrying the bombs dives at high speed from a high altitude, the axis of the plane being directed upon the target. During the latter course of the dive, the pilot or operator must accurately follow the target and direct the axis of his dive at a precise point on or immediately ahead of the target. At a predetermined minimum altitude above the target the bombs are released and the plane rapidly changes its course pulling out of the dive and away from the target. The bombs continue along a line of travel which is an extension of the direction of the plane's diving attack and are expected to hit the target.

Very often a pilot becomes engrossed in the problem of maintaining the axis of his plane directed at the target and may find himself either diving at a 90° angle (perpendicular to the horizontal) or at an angle in excess of 90°, under which conditions the plane is virtually on its back. Diving under such conditions is dangerous and the pull-out is extremely hazardous in that it subjects the pilot and the plane to tremendous centrifugal forces which may destroy the plane itself or at least cause the pilot to lose consciousness for a prolonged period of time with sometimes disastrous results.

The present invention is directed to a gun sight which is employed by the pilot during the dive and which includes a dive indicator, thereby permitting the pilot not only to accurately direct the course of his plane but at the same time maintain a desired angle of dive. At all events, the pilot is informed as to when he reaches the preferred angle of attack without having to remove his eyes from the gun sight. It is to be remembered that during a diving attack it is essential for the pilot to maintain his eyes on the target and that if it is necessary for him to move his head or eyes for even a brief instant, the altitude lost or the deviation from the course may render the dive ineffective.

It is an object of the present invention, therefore, to disclose and provide an improved gun sight provided with means whereby the diving angle of the aircraft equipped with the sight is indicated.

A further object of the invention is to provide means associated with a telescopic gun sight whereby the diving angle of the aircraft is indicated within the field of view of the sight.

10 Other objects of the invention will become apparent from the following description of certain illustrative forms of the invention.

In order to facilitate understanding, reference will be had to the appended drawing, in which:

15 Fig. 1 indicates the position of a military plane executing a diving attack.

Fig. 2 is a longitudinal section of one form of telescopic sight equipped with the means of this invention.

20 Fig. 3 is a transverse section taken along the plane III—III of Fig. 2.

Fig. 4 is a section taken along the plane IV—IV of Fig. 3.

25 Fig. 5 is an isometric representation of the main elements of the dive indicator in improved form.

In Fig. 1 the airplane 1 is executing a dive at an angle of 70° to the horizontal and for the purposes of this discussion, it may be assumed that 70° is the preferred angle of attack during dive bombing. It will be evident that if the angle of attack is increased to say 90° or therebeyond, it is more difficult for the pilot to control his plane and the dangers of pull-out are greatly increased, as previously stated.

30 During the dive, the pilot directs his plane by the use of a gun sight generally indicated at 2, this gun sight being an integral part of the plane 1, the axis of the sight 2 being parallel to the axis of the plane. A longitudinal section through

40 a telescopic gun sight is shown in Fig. 2 and as there shown the sight comprises a barrel provided with a plurality of lenses, such as the objectives 4 and 5 and the oculars 6 and 7. A reticule glass is indicated at 8 and a resilient or yielding eye rest is indicated at 9.

Attached to the tubular body of the gun sight 2 is a housing 10 containing a dive indicator whose index member 11 extends through a suitable opening or slit 12 formed in the side of the 45 tubular body portion of the telescopic gun sight 2 at a point closely adjacent the reticule glass 8 and preferably between the reticule glass and eye piece of the sight. As shown more particularly in Fig. 3, the index member 11 may normally lie in the position indicated by dotted lines and

therefore out of the central portion of the field of view through the telescope. Its presence would ordinarily not be observed by the user of the sight. In the event the aircraft on which the gun sight is mounted is executing a dive at an angle of 70°, the index member 11 will occupy the full line position shown in Fig. 3 and thereby inform the pilot as to his diving angle while the pilot is observing the target through his sight.

The dive indicator associated with the gun sight should include, in addition to an indicator movable substantially in the focal plane of the sight, some damping means whereby minute variations or shifts in the angle of attack are not immediately indicated. Damping means thus prevent the indicator from fluttering or vibrating unnecessarily. Furthermore, in interests of economy and simplicity, it is desirable that the indicating means be operated by gravity.

In the exemplary form illustrated in Figs. 2, 3 and 4, the auxiliary housing 10 contains a jack shaft 14 on which the indicator 11 is mounted. The shaft 14 also includes a spiral gear 15 which is in engagement with another spiral gear 16 carried by the shaft 17. The shaft 17 extends through a gland or oil-tight bearing 18 into a chamber 19. The chamber 19 may be capped with a removable end member 20 carrying a bearing adapted to receive the end of the shaft 17. The other end of the shaft may be journaled in a bearing or mounting 21. The shaft 17 is shown provided with an unbalanced member 24 which may be either keyed or otherwise attached to the shaft 17.

The member 24 may be in the form of a paddle provided with a plurality of apertures 25, 26, and the like, these apertures having outwardly flaring side walls leading to a restricted bore.

The chamber 19 is preferably filled with a non-freezing liquid whose viscosity characteristics are not materially altered or changed due to variations in temperature. Preferred liquids should have a freezing point well below -40° F. and should not exhibit material changes in viscosity at temperatures between about -40° F. and 80° F. Moreover, the preferred liquids should not vaporize readily. There are various liquids adapted for use under the conditions encountered, among them being glycol derivatives, tetradecane, quinoline, octyl alcohol, phenyl isothiocyanate, and solutions of bromates and iodides, etc.

It is to be understood that the form of the invention here specifically described is simply illustrative of one form that the invention may take, and that numerous changes and modifications can be made, as will be evident to skilled workers in the art.

The chamber 19 may be provided with a relatively large filling cap 30 through which the damping liquid may be introduced, the neck of said filling port being sufficiently long so as to permit the liquid to completely fill the chamber 19. Extending inwardly from the side walls of the chamber 19 stops or anti-splash baffles, such as the baffles 31 and 32, may be provided, these baffles or stops being suitably reticulated or perforated. These baffles prevent violent surging of the liquid within the chamber 19 without preventing circulation.

Those skilled in the art will appreciate that the unbalanced member 24 shown in Fig. 4, occupies the position had by the member when the telescopic gun sight has its axis substantially parallel to the horizon. Under diving conditions,

the unbalanced member 24 will hang downwardly but the housing 10 and telescopic sight will be inclined so that the baffle 32 will be very much closer to the member 24. The movement of the

member 24 within the body of liquid in the chamber 19 is impeded somewhat by the damping fluid within the chamber. The bores or perforations 25 and 26 permit fluid to pass through the unbalanced member 24, the amount of resistance or the extent of the damping effect depending somewhat upon the viscosity of the fluid within the chamber and the number and size of the perforations 25 and 26 formed in the member 24. The resistance of the dive indicator may be modified by changing the fluid and by changing the number and size of ports in the unbalanced member. The damping is particularly desired at the beginning of a dive where the plane rapidly changes its angle of attack from 0° to 20 say 70° and it is important that this rapid change in the axis of the aircraft be absorbed without setting up unnecessary oscillations of the unbalanced member 24.

The schematic arrangement shown in Fig. 5 shows an unbalanced member 24 but the shaft on which this unbalanced member is mounted, and indicated at 37, is provided with a crank 38 connected as by means of a link 36 to the index member 35 which is pivoted at 34. The link 36 is attached to the end of index member 35 and to the crank 38 by small universal or toggle joints. This simple form of construction eliminates the use of gears such as the gears 15 and 16, and may be entirely satisfactory for use in training planes.

As previously pointed out, the present invention permits the pilot of the plane to maintain his target in sight and at the same time know when he has reached or is exceeding the predetermined angle of dive. The critical diving angle as well as other diving angles approximating the critical angle may be engraved or marked upon the reticule glass 8 so as to facilitate reading of the index member 11. The extent of movement of the index member will, of course, depend upon the size of the port 12 and upon the gear ratio between the gears 15 and 16.

Although a specific form of the invention has been described, it is to be understood that the invention is not limited thereto, the exemplary form being described simply for purposes of illustration. All changes and modifications coming within the scope of the appended claims are embraced thereby.

I claim:

1. In combination with a gun sight fixedly mounted on an air craft: a housing fixedly attached to the gun sight; gravity responsive actuating means in said housing, said actuating means being movable in a plane parallel to the axis of the gun sight and about an axis perpendicular to the optical axis of the gun sight; and an indicator member operably attached to the gravity responsive actuating means, said indicator being movable in a plane substantially perpendicular to the optical axis of the gun sight and to extend from the housing into the focal plane of the gun sight.

2. Gravity responsive means for indicating the inclination of a gun sight provided with a barrel, an eye piece and a lens system, comprising: a housing adapted to be fixedly attached with respect to the barrel of the gun sight; an indicator member extending from said housing into said barrel and movable in a plane trans-

verse to the optical axis of said lens system; gravity responsive means in said housing, said means being movable in a plane parallel to the axis of the gun sight and about an axis perpendicular to the optical axis of the gun sight; and means for translating movement of the gravity responsive means into movement of the indicator.

3. Gravity responsive means for indicating the inclination of a telescopic gun sight fixedly mounted on an aircraft, comprising: a housing adapted to be fixedly attached to the tube of

5 the gun sight; gravity responsive actuating means in said housing, said actuating means being movable in a plane parallel to the axis of the gun sight and about an axis perpendicular to the optical axis of the gun sight; and an indicator member operably attached to the gravity responsive actuating means, said indicator being movable in a plane substantially perpendicular to the axis of the gun sight and adapted to extend from the housing into the line of sight through said gun sight.

RUSSELL R. VOUGHT.
